UNITED STATES PATENT OFFICE.

GEORGE BODEN, OF WATERBURY, CONNECTICUT, ASSIGNOR, BY MESNE ASSIGNMENTS, TO SCOVILL MANUFACTURING COMPANY, OF WATERBURY, CONNECTICUT, A CORPORATION OF CONNECTICUT.

MARKING PIN.

Application filed June 9, 1921. Serial No. 476,137.

To all whom it may concern:

Be it known that I, GEORGE BODEN, a citizen of the United States, residing at Waterbury, county of New Haven, and State of Connecticut, have invented certain new and useful Improvements in Marking Pins, fully described and represented in the following specification and the accompanying drawings, forming a part of the same.

10 This invention relates to certain improvements in marking pins.

Safety pins carrying a marking plate are well-known in the art. These pins are used for various purposes, an important use being 15 in laundries. The marker plate on the pin carries a number or other symbol, and the articles belonging to the same batch of laundry are marked with the same number or symbol. The marker is sometimes formed 20 by a plate which is affixed to one of the legs of the safety pin; sometimes the marker is affixed to the cap which receives the pointed end of the pin, and constructions have been proposed in which the marker plate is carried 25 on the bow end of the pin, the plate lying to one side of the bow and having a flange which is bent over the bow to secure the plate thereto. The latter construction has certain advantages, but in the constructions 30 referred to the marker plate is so fixed to the bow end of the pin that a crevice is formed between the pin and the plate. When the pin is inserted into the fabric, the fabric is liable to be crowded into the crevice between 35 the marker plate and the pin during the laundry operations and is frequently torn. Further, the marker plate, which is of thin sheet metal, was so attached to the pin that a part of the outer edge was exposed 40 and this exposed edge was liable to cut or injure articles with which it came in contact during the laundry operations.

One of the objects of this invention is to 45 produce a marking pin which shall have the marker plate fixed to the bow end of the pin, the plate being secured to the pin in such a way that there is no crevice in which the goods can be caught.

A further object of the invention is to 50 produce a marking pin in which the outside sharp edge of the marking plate shall be guarded in such a way that it will not come in contact with the articles during the laundry operations.

A further object of the invention is to 55 produce a pin which while of convenient size shall afford proper space between the cap carrying bar and the leg of the pin so that stringing operations are facilitated.

With these and other objects not referred to in view, the invention consists in certain constructions, improvements and combinations of parts which will be hereinafter fully described and then specifically pointed out.

Referring to the accompanying drawing: 65

Figure 1 is a view of the improved pin in side elevation.

Figure 2 illustrates the pin with the fabric threaded thereon.

In the drawing which illustrates a preferred construction of pin embodying the invention, 1 indicates the pointed leg of the pin and 2 the cap carrying bar, the cap which receives the pointed leg of the pin when the pin is closed being indicated at 3. 70 The pointed leg and the cap carrying bar are connected by a bow 4 to which the marker plate is secured. In the best constructions embodying the invention, the pointed leg will be disposed at an angle to the bow, the point of juncture between the bow and the pointed leg which forms the apex of the angle being indicated at 7. The marker plate is indicated at 5, and is provided with a flange 6 by which the plate is secured to 75 the bow, the flange being bent over the bow. In the improved construction, when the parts are assembled, the end of the flange 6 which is on the pointed leg side of the bow and which is marked 8, lies near the inner 80 edge of the plate and also close to the angular point 7. With this construction, very little of the metal of the marker plate lies forward of or inside the point where the flange is connected to the bow. It follows, 85 therefore, that no substantial crevice exists between the pointed leg and the metal of the marker plate, and one will not be formed by the springing back of the thin edge of the plate during use. When, therefore, the fabric is threaded on the pin, as shown in Fig. 2, it will not be caught between the 90 plate and the pointed leg.

In the best constructions, furthermore, embodying the invention, the cap carrying 100 bar will be curved upwardly between the point of attachment of the flange with the marker pin and the cap, or, in other words,

the cap carrying bar slopes from its high point toward the end of the flange 6 on one side and toward the cap on the other. This curve of the cap carrying bar accomplishes two important functions. The bar guards the outside edge of the marker plate so that when the article to which the marker pin is attached is going through the laundry operations, there is no sharp outside edge which can come in contact with other articles in the batch of laundry. Further, when the articles to which these markers are attached reach the sorting bench of the laundry, they are strung on bars, the bars passing between the leg and the cap carrying bar. This outward curve of the cap carrying bar increases the space between it and the leg, and therefore, makes it easier to place it on the sorting bar.

20 What I claim is:

1. A marking pin comprising a bow, a pointed leg and a cap carrying bar, and a flanged marker plate having its flange bent

over the bow to secure the plate to the bow, the end of the flange on the pointed leg side 25 of the bow lying near the inner edge of the marker plate, and the cap carrying bar being curved upwardly away from the pointed leg with the concave side of the curve toward the pointed leg and so disposed with 30 respect to the edge of the marker plate that it acts as a guard for the edge of the plate.

2. A marking pin comprising a bow, a cap carrying bar and a pointed leg, and a flanged marker plate having its flange bent over the 35 bow to secure the plate to the bow, the flange and the cap carrying bar being curved upward away from the pointed leg with the concave side of the curve toward the pointed leg and so disposed with 40 respect to the edge of the marker plate as to act as a guard therefor.

In testimony whereof, I have hereunto set my hand.

GEORGE BODEN.
